Patented Apr. 2, 1968

210,656

AUTOMOBILE HEADREST BRACKET

Paul P. Longo and Allen Parmet, both of E. State St.
and High St., Camden, N.J. 08105

Filed Sept. 14, 1966, Ser. No. 3,952

Term of patent 14 years

(Cl. D14—6)

FIG. 4

FIG. 5

FIG. 6

FIG. 1 is a perspective view showing our novel automobile headrest bracket.

FIG. 2 is a side elevational view thereof, the other side being exactly similar and opposite.

FIG. 3 is a front elevational view thereof.

FIG. 4 is a top plan view thereof.

FIG. 5 is a rear elevational view thereof.

FIG. 6 is a bottom plan view thereof.

The elements shown in broken lines are included for illustrative purposes only.

We claim:

The ornamental design for an automobile headrest bracket, as shown and described.
